DISPLAY SIGN

Robert M. Meisel, Detroit, Mich.

Application October 3, 1935, Serial No. 43,292

2 Claims. (Cl. 40—138)

My invention relates to a new and useful improvement in a display sign and has for its object the provision of a display sign provided with a stationary supporting body mounted upon which is a display body spaced outwardly from the supporting body and moveable relatively thereto.

It is an object of the present invention to provide a display sign in which a moveable body shall be so mounted upon the supporting body that upon a jarring of the supporting body, the moveable body will oscillate or move relatively to the supporting body so as to attract attention.

Another object of the invention is the provision of a display sign so arranged and constructed that the moveable supporting body will be supported in a plane parallel to the supporting body and in its movements remain in a plane parallel to the supporting body.

Another object of the invention is the provision in a display sign of a moveable display member mounted on a supporting body in such a manner that it will move relatively thereto upon a jarring of the supporting body, while remaining in a plane parallel to the supporting body, on an axis lying within the moveable display body.

Another object of the invention is the provision of a display sign having a supporting body with a moveable display member mounted thereon and adapted to move relatively thereto bodily without changing its inclination to the supporting body, upon a jarring of the supporting body.

Other objects will appear hereinafter.

The invention consists in the combination and arrangement of parts hereinafter described and claimed.

The invention will be best understood by a reference to the accompanying drawing which forms a part of this specification, and in which,

Fig. 1 is a front elevational view of a display sign embodying the invention.

Fig. 2 is a fragmentary, front, elevational view of the display sign embodying the invention in a slightly modified form.

Fig. 3 is a fragmentary, front, elevational view of a display sign embodying the invention in a slightly different modified form.

Fig. 4 is a sectional view taken on line 4—4 of Fig. 1.

Fig. 5 is a sectional view taken on line 5—5 of Fig. 1.

Fig. 6 is a sectional view taken on line 6—6 of Fig. 2.

Fig. 7 is a sectional view taken on line 7—7 of Fig. 3.

As shown in the drawing, the invention comprises a supporting body 9 which may be used for displaying advertising and the like. Mounted on the exposed face of the body 9 is a block 10 to one end of which is attached a resilient supporting bar 11, preferably made from spring metal. This bar 11 is bent intermediate its ends as at 12 and the opposite end is fastened to a block 13 which is mounted on the inner face of the moveable display member 14. The exposed face of the member 14 carries advertising and when the member 14 is mounted in a body subject to jars, such as a bus, street car or the like, the member 14, upon a jarring of the member 9, will move relatively to the member 9 and in the form shown in Fig. 1 this movement will be a vertical movement. The member 14 lies in a plane parallel to the member 9 and in its movement upwardly and downwardly, the member 14 will move in this plane which is parallel to the plane of the body 9.

In Fig. 2 I have illustrated a slightly modified form of construction in which the moveable display body 14' carries on its inner face a block 13'. The supporting body 9 is provided with the block 10 to which one end of the supporting bar 11 is connected. This supporting bar is bent from the edge of the block 13' downwardly and at its lower end this bar is again angularly-turned as at 15 and attached to the lower surface of the block 13'. In the form shown in Fig. 1 the supporting bar 11 is connected to the upper surface of each of the blocks and in the form shown in Fig. 2 it is connected to the upper surface of the block 10 and to the lower surface of the block 13'. Consequently, when the supporting body 9, in the form shown in Fig. 2, is subjected to a jarring, the display body 14' will oscillate or rock on an axis within itself which is substantially midway between the two blocks. This rocking or oscillating movement is always in the plane parallel to the plane of the supporting body 9 as the member 14' is mounted in such a plane.

In the form shown in Fig. 3 the display body 9 carries a block 10 to one end of which is attached a wire or supporting bar 11'. The opposite end of this bar is attached to the block 13' carried by the display body 14'. It will be noted that the bar 11' is bent as at 12'. The function and operation of the form shown in Fig. 3 is substantially the same as that shown in Fig. 1 excepting that the display body 14''

extends at an inclination to the supporting body 9. This body 14", however, lies in a plane parallel to the plane of the body 9 and the same oscillating movement is effected.

5 In each of the forms shown, the blocks serve as spacing members to retain the parts in separated relation but the mounting of the supporting bar 11 is such that ordinarily the block carried by the display body does not contact with 10 the face of the supporting body.

When a display sign such as illustrated is mounted in position where it is subject to jars, as in a street car, bus or the like, the display body which is supported on the supporting body 15 by the resilient bar will continue to bob or move so as to attract attention.

It will be noted that the supporting bar in each instance extends parallel to the supporting body and also parallel to the display body. 20 This is so because if a coil spring or the like were to be fastened at one end to the supporting body and at its opposite end to the display body, while the bobbing and oscillating or relative movement would be obtained, there would be a tilting of the display body relatively to the 25 supporting body which is a very undesirable feature in a display sign of this kind. When the supporting sign is extended parallel to the supporting body and the display body mounted in a plane parallel to the supporting body, the advertising displayed on the outer face of the display body may be read at all positions of its 30 movement. This is due to the fact that the plane of the display body does not tilt relatively to the plane of the supporting body and is effected by retaining the supporting bar in the parallel 35 extension referred to.

While I have illustrated and described the preferred form of construction, I do not wish to

limit myself to the precise details of structure shown, but desire to avail myself of such variations and modifications as may come within the scope of the appended claims.

Having thus described my invention, what I 5 claim as new and desire to secure by Letters Patent is:

1. A display sign comprising a supporting body having a planal face; a block secured on said face; a display member having a planal face 10 opposed to the planal face of said supporting body and in spaced relation parallel thereto; a block secured on said planal face of the display member and out of registry with the supporting body block; and a leaf spring disposed between 15 said planal faces with its transverse plane perpendicular thereto, one end of said leaf spring being secured to one of said blocks, and the other end of the spring being secured to the other block. 20

2. A display sign comprising a supporting body having a planal face; a block secured on said face and having a flat surface perpendicular thereto; a display member having a planal face opposed to the planal face of the supporting body 25 and in spaced relation parallel thereto; a second block secured on said planal face of the display member out of registry with the first named block and having a flat surface perpendicular to the display member face and on the far side of the 30 block with respect to the flat surface on the first named block; and a leaf spring disposed between said planal faces with all points of its transverse plane perpendicular thereto, one end of the spring being secured to the flat surface on 35 one block, and the other end of the spring being secured to the flat surface on the other block.

ROBERT M. MEISEL.
